TRAFFIC SIGNAL SYSTEM

Joseph N. Paul, Fort Wayne, Ind., assignor, by
mesne assignments, to Automatic Signal Cor-
poration, East Norwalk, Conn., a corporation
of Delaware

Application January 17, 1938, Serial No. 185,322

12 Claims. (Cl. 177—337)

This invention relates to a traffic signal system. It is particularly applicable to a coordinated system of signals at successive intersections along a main business street or highway where the traffic on one or more of the cross streets is subject to wide fluctuations in volume. Certain features of the invention, however, are adapted for isolated intersections not included in a coordinated system.

10 One object of the invention is to prevent unnecessary interruptions in main highway traffic when such interruptions are not required by cross street traffic.

Another object of the invention is to eliminate 15 such unnecessary interruptions without disturbing the coordination of signals at the several intersections of a coordinated system.

In coordinated systems the interruptions to the main street traffic at successive intersections may 20 be timed as nearly as possible to permit uninterrupted passage of a vehicle along the main street at a predetermined speed, or they may occur simultaneously at all cross streets, or simultaneously at alternate cross streets. In each 25 of these types of coordination, it is important that the interruptions to main street traffic at the several intersections take place in timed relation with each other.

A single coordinated system may include in- 30 tersections at which the cross street carries a substantial volume of traffic at all times and other intersections at which the cross street carries little or no traffic at certain hours. For any coordinated system, the present invention pro- 35 vides time controlled apparatus for timing at each intersection a succession of periods during which right of way always remains in the highway, said periods at the several intersections being coordinated in any desired time relation. 40 At intersections of the first type mentioned above, these periods are alternated with cross street right of way periods in the usual manner. At intersections of the second type, the main street right of way periods are alternated with po- 45 tential cross street right of way periods during which right of way may or may not be granted to the cross street, depending upon whether or not a vehicle or vehicles are present in the cross street requiring such right of way. Traffic 50 actuated detectors are placed in the cross street to indicate the presence of such vehicles and when actuated, they serve to condition the apparatus so that the next potential cross street right of way period becomes an actual right of 55 way period for the cross street. In the absence

of such actuation, right of way remains with the main street during the potential period. Obviously, a single coordinated system may include intersections of the second type only, in which case traffic actuated means for converting potential right of way periods into actual right of way periods are located at all of the intersections. 5

For use at an isolated intersection not forming a part of a coordinated system, the invention provides means for timing main street right of way periods alternated with potential cross street right of way periods, together with traffic actuated means for converting the potential periods into actual right of way periods for the cross 10 street when required by traffic. 15

Other objects and features of the invention will be understood from the accompanying drawings and the following description and claims:

Fig. 1 is a plan view of a main street inter- 20 sected by a number of cross streets showing a desirable location for the traffic signals and traffic actuated devices used to indicate the presence of vehicles in the cross streets.

Fig. 2 is a diagrammatic view of a detector 25 relay used with the particular type of traffic actuated apparatus herein disclosed.

Fig. 3 is a sectional view taken on the line 3—3 of Fig. 4 and showing the construction of a preferred form of traffic actuated device. 30

Fig. 4 is a longitudinal sectional view of the same. 35

Figs. 5 and 5a together constitute a diagram showing in a preferred form the wiring for the apparatus controlling the first four intersections of Fig. 1. Conductors marked "X" in Fig. 5 are connected to those marked "X" in Fig. 5a.

Fig. 6 is a sequence table showing the time of operation of the several switches, signals, etc. for an illustrative sequence of operations of the apparatus used for the first two intersections of Fig. 1. 40

Fig. 7 is a simplified diagram in across-the-line form of the electrical apparatus for one of 45 said intersections.

In the following specification, the invention is illustrated as applied to a coordinated system of the type disclosed in Bechtold Patent No. 1,951,816. However, certain features of it may 50 be applied equally as well to isolated intersections and to other types of coordinated systems, such as those in which a single controller times the periods for all intersections and those in which secondary controllers for each intersection 55

are operated by synchronous motors whose speed is controlled from a central point.

In Fig. 1, there is illustrated a main street intersecting several cross streets of which the third and fourth are assumed to be of the first class carrying an appreciable amount of traffic at all times, while the first and second are assumed to be of the second class carrying little or no traffic at certain hours. Signals L are provided at each intersection to indicate right of way to the main street and cross streets. These signals may be in the form of the well known red, green and amber signal lamps commonly used for the purpose. Traffic actuated detectors D are placed in the cross street approaches to the intersections of the second class in position to be actuated by vehicles approaching the intersections but not by vehicles leaving the same. These detectors are preferably of the magnetic type illustrated in detail in Figs. 3 and 4. Other electrical elements shown in Figs. 5 and 5a may be housed in suitable control boxes at convenient points, preferably adjacent the intersections. The individual elements of the apparatus will each be first described in detail.

Traffic actuated detectors

Each detector (Figs. 3 and 4) includes a core consisting of a bar 11 of permanently magnetized steel surrounded by a group of soft iron rods 12. Surrounding the rods 12, there are provided a plurality of spools 13 upon each of which there is wound a coil 14 of insulated wire. The coils are electrically connected by conductors 15 and the coil at one end is connected to conductors 16 and 17 leading through a suitable conduit 18 to the control box. The core and coils are enclosed in a pipe 19 of non-magnetic material, preferably the material known commercially as Transite, as marketed by Johns-Manville Sales Corporation for example. Plugs 20 serve to close the ends of the pipe 19 and one of said plugs receives the conduit 18. The core and coils are held in place within the pipe 19 by a filling 21 of a waterproofing material, such as paraffin.

The detectors are buried beneath the pavement or are cast within the concrete paving slab if put in position simultaneously with the pavement. Each detector is made sufficiently long so that a car approaching the intersection must pass through at least a part of its magnetic field. The magnetic field of each detector extends beyond the ends of the detector about half the length of the detector itself. A detector six feet long placed centrally in a traffic lane 22 feet wide will be actuated by any car passing in that lane. For narrower lanes, shorter detectors may be used. For wider lanes, two or more detectors preferably are used. For a six-foot detector, preferably three of the coils 14 are used, each about 20 inches long. The magnetized bar 11 provides a magnetic field, a part of which extends above the highway surface. The soft iron rods 12 increase the permeability of the core and thus increase the change in lines of magnetic force actually threading the coils 14 which results from the passage of a vehicle containing magnetic material. When the magnetic field is disturbed by the passage of a vehicle, the resulting change in the number of lines of magnetic force threading the coils 14 induces an electro-motive force therein which is applied through the conductors 16 and 17 to the electric units in the detector relay.

Detector relays

At each of the intersections having traffic actuated detectors there is provided a detector relay shown in diagrammatic form in Fig. 2. The relay unit includes a coil A pivotally mounted in a gap in the field of a permanent magnet 22 and carrying a needle 23 movable by movement of the coil A in the well known manner of a D'Arsonval galvanometer. The needle 23 carries a small armature 24 adapted to engage a stationary contact member 25. Armature 24 is of magnetic material and member 25 is permanently magnetized and thus attracts and holds said armature when the needle 23 is moved sufficiently to bring the armature into the magnetic field. Armature 24 and contact member 25 together form an electric switch referred to hereinafter as switch a.

Adjacent the switch a there is provided a motor B on the shaft of which there is mounted an insulation block 26 carrying a plurality of strikers 27 each adapted to strike the end of the needle 23 in the rotation of the motor and thus to break the same free from the magnetic contact member 25. The insulation block also carries a metallic contact plate 28 having a plurality of indentations 29 in the periphery thereof and engaged by the tips of a pair of resilient contact fingers 30 and 31. So long as both contact tips engage plate 28 current may flow between them. The contact finger 31 is in the path of travel of the indentations 29 and when one of said indentations engages said finger the electrical connection between said fingers is broken. The fingers 30 and 31 and plate 28 constitute an electric switch hereinafter referred to as switch b.

Master timer

The coordination of the system is maintained by a master timer, indicated by name in Fig. 5. This timer is herein shown as a motor driven switching unit in which an induction disc 32 is driven by a motor coil M and in turn rotates a series of cams 33 adapted to open and close switches m1, m2, m3 and m4 in a predetermined sequence. The speed of operation may be adjusted by various means such as shading coils or adjustable pole pieces well known in the art pertaining to induction disc motors. While the timer is shown in the drawing in a conventionalized form, a timer is preferably used such as that disclosed in Bechtold Patent No. 1,926,833.

Secondary timers

At each of the intersections of the second class there is provided a secondary timer indicated by name in Fig. 5 and similar in type to the master timer. Each secondary timer includes an induction disc 34 driven by any one of three motor coils, H1, H2 and H3, and in turn operating a series of cams 35 to open and close a series of switches h1, h2, h3, h4, h5, h6, h7, h8, h9, h10 and h11 in a predetermined sequence. The motor coils H1, H2 and H3 are arranged so that all drive the timer in the same direction and each drives at a speed which may be adjusted as desired.

For intersections of the first class, there are provided secondary timers indicated by name in Fig. 5a which are similar to those just described for the second class intersections except that certain of the switches are not used.

Relays

At each of the second class intersections there are provided a direct current relay C and alter-

nating current relays E and F of the magnetic type. Relay C when energized closes normally open switches c1 and c2, relay E when energized closes normally open switches e1 and e2 and relay F when energized closes normally open switches f1, f2, f3 and f4 and opens normally closed switch f5.

Signals

At each intersection the signal lamps are indicated by the notations MG, MA, MR, CG, CA, CR for the main street go, caution and stop signals and the cross street go, caution and stop signals respectively. For simplicity, only one set of lamps is shown for each intersection but as many sets as desired may be connected in parallel.

Power supply

Power supply is preferably alternating current of a commercial voltage and frequency and may be supplied from a single pair of power mains or from local power lines at the several intersections, with a separate supply for the master control. In the present example, the latter method is used, the mains for the master controller being indicated "Master AC" in Fig. 5 and those for the intersections being indicated "Local AC". A service switch SM is connected to the Master AC mains and supplies a pair of distributary conductors 36 and 37. Service switches SL are similarly connected to the local AC mains at each intersection and supply local distributaries 38 and 39. At each of the second class intersections direct current is supplied to distributaries 40 and 46 by a rectifier R supplied with suitable low voltage alternating current from a transformer T connected to the local distributaries 38 and 39.

Circuits tabulated

In describing the wiring connections, conductors are referred to by number only in tracing the circuits of which they form a part. Conductors having more than one branch carry the same reference number throughout their several branches. Circuits are referred to as circuits No. 1, No. 2, etc. and are identified by number in Fig. 7 for the first intersection. The numbered circuits for this intersection are tabulated and traced below for convenience of reference:

Circuit No. 1: D, 16, A, 17, D. Energizes detector relay coil A when detector is actuated.

Circuit No. 2: R, 40, resistance 41, 42, push button p, 17, A, 16, R. Direct current circuit energizes coil A when push button p is pressed by a pedestrian.

Circuit No. 3: R, 40, a, 43, C, 16, R. Direct current circuit for energizing relay C.

Circuit No. 4: SL, 38, h2, 44, e2, 45, c1, 46, B, 39, SL. Energizes motor B.

Circuit No. 5: SL, 38, b, 46, B, 39, SL. Energizes motor B after circuit No. 4 is broken.

Circuit No. 6: SL, 38, h1, 47, c2, 48, E, 39, SL. Energizes relay E.

Circuit No. 7: SL, 38, h8, 49, e1, 48, E, 39, SL. Holding circuit for relay E.

Circuit No. 8: SL, 38, h1, 47, c2, 48, F, 39, SL. Energizes relay F.

Circuit No. 9: SL, 38, h9, 49, e1, 48, F, 39, SL. Holding circuit for relay F.

Circuit No. 10: SL, 38, h5, 50, f3, 51, MR, 39, 70 SL. Displays red stop signal for main street.

Circuit No. 11: SL, 38, h5, 50, f3, 51, CG, 39, SL. Displays green go signal for cross street.

Circuit No. 12: SL, 38, h5, 50, h4, 52, f4, 53, CA, 39, SL. Displays amber caution signal for cross street.

Circuit No. 13: SL, 38, h5, 50, h3, 54, H3, 39, SL. Energizes secondary timer motor coil H3.

Circuit No. 14: SL, 38, h6, 55, h8, 54, H3, 39, SL. Also energizes motor coil H3.

Circuit No. 15: SL, 38, h6, 55, h7, 56, f1, 57, 5 MA, 39, SL. Displays amber caution signal for main street.

Circuit No. 16: SL, 38, h6, 55, f2, 58, CR, 39, SL. Displays red stop signal for cross street.

Circuit No. 17: SL, 38, f5, 58, CR, 39, SL. Also displays cross street stop signal.

Circuit No. 18: SL, 38, h6, 55, f2, 58, MG, 39, SL. Displays green go signal for main street.

Circuit No. 19: SL, 38, f5, 58, MG, 39, SL. Also displays main street go signal.

Circuit No. 20: SM, 36, m4, 59, h10, 60, H1, 37, 15 SM. Energizes the secondary timer motor coil H1.

Circuit No. 21: SM, 36, m3, 61, h11, 62, H2, 37, 20 SM. Energizes the secondary timer motor coil H2.

Coordination of timer operations

The master timer runs continuously since its motor coil M is connected directly across the distributaries 36 and 37. Its switches are opened and closed in the sequence shown in Fig. 6 in which shaded areas indicate the portion of the cycle in which the several switches are closed. Each of the secondary timers divides the cycle into several periods indicated in Fig. 6—"Main 25 idle", "Main run", "Change", "Cross idle" and "Cross run", followed by a second "Change" period. Taking the first of the secondary timers as an example and assuming that the cycle starts in the Main idle period, the secondary timer is 30 at rest since none of its motor coils H1, H2 or H3 is energized. At the end of this period switch m3 in the master timer is closed, completing circuit No. 21 to energize the motor coil H2. The duration of the idle period thus depends upon the 35 speed of operation of the master timer.

The motor coil H2 runs the secondary timer through the Main run period at the end of which switch h11 is opened to break circuit No. 21 and deenergize the motor coil H2. The duration of this period thus depends upon the speed at which the coil H2 is permitted to operate the secondary timer.

Simultaneously with the end of the Main run period switch h8 is closed, completing circuit No. 14 to energize the motor coil H3 which runs the timer through the change period. The duration of the change period depends upon the adjustment of the speed resulting from the operation 50 of coil H3.

At the end of the change period, switches h6 and h8 are opened to deenergize coil H3. Switch h10 in circuit No. 20 for the coil H1 is closed but does not complete the circuit since switch m4 in the master timer is open. The secondary timer therefore comes to rest and remains so during the Cross idle period.

At the end of the Cross idle period, switch m4 is closed, completing circuit No. 20 for coil H1 to 65 run the timer through the Cross run period. At the end of this period, switch h10 is opened to break circuit No. 20 and switch h3 is closed to complete circuit No. 13, switch h5 in this circuit having been previously closed. Circuit No. 13 70 energizes motor coil H3 to run the timer through the second Change period. At the end of this period, switches h5 and h3 are opened to stop the timer in the main idle position and switch h11 is closed to condition circuit No. 21 for the 75

next operation of switch *m3*. The cycle is thus complete.

By the means just described, each secondary timer predetermines a sequence of timed periods under the control of the master timer. Minor adjustments in the duration of the periods may be made by adjustments of the speed of operation of the secondary timer motor coils *H1*, *H2* and *H3*. Major adjustments in the relation of the periods may be made by connecting switches *h10* and *h11* to the several master timer switches. For example, at the second intersection, the times of starting the Main run and Cross run periods are offset one-half cycle from those of the first intersection by connecting switch *h10* to switch *m3* and switch *h11* to switch *m4*. At the third intersection, switches *h10* and *h11* are connected by conductors *63* and *64* to switches *m1* and *m2* respectively, thus off-setting the start of the running periods from those at the first intersection by one-fourth of a cycle. At the fourth intersection, the connections are the reverse of those at the third. Whatever the adjustments may be, the periods at each intersection occur in a definite timed relation to those at the other intersection. The timing of the entire system may be affected by varying the speed of the master timer without destroying the coordination of the system.

30 *Signal operation—second class intersections*

Signal operation at the second class intersections may be divided into three general cases; Case I, operation in response to a traffic actuation occurring during a Main idle or Main run period; Case II, operation in response to a traffic actuation occurring during a Cross idle, Cross run or Change period; and Case III, operation in the absence of traffic actuations. In the assumed sequence of operations indicated in Fig. 6, Cases I and III are illustrated by the operation at the first intersection and Case II by the operation at the second intersection.

45 *CASE I.—Traffic actuation during Main idle or Main run periods*

Referring now to the operation at the first intersection as indicated in Fig. 6, it is assumed that operation begins in the Main idle period and that no traffic actuations have occurred for some time previous. Circuits Nos. 17 and 19 are complete to display the green signal for the main street and the red signal for the cross street. Since these circuits do not pass through the switches of the secondary timer, the signals are not at this time under the control of said timer. All other circuits are incomplete except circuit No. 1 in which no current flows until a detector *D* is actuated.

With the apparatus in this condition, it is assumed that a vehicle approaches the intersection in the cross street and actuates one of the detectors *D*. The resulting electromotive force generated in the detector causes current to flow in circuit No. 1, first in one direction as the vehicle enters the detector magnetic field and then in the other direction as it leaves said field. This current deflects coil *A* and moves needle *23* either directly toward contact member *25* or first 70 away from said member and then toward the same. In either case, the armature *24* is caught by the magnetic contact member *25* and held thereby to close switch *a*. It is to be noted that when two detectors are used at an intersection 75 as shown in Fig. 1, they are connected in parallel

and the actuation of either causes the closing of switch *a*.

Coil *A* may also be energized to close switch *a* by the operation of the pedestrian push button switch *p* which completes circuit No. 2 to supply direct current to coil *A*. Although only one such push button is shown in the drawing, it is obvious that as many as needed may be connected in parallel.

The closing of switch *a* completes circuit No. 3 10 to energize relay *C*, closing switches *c1* and *c2*. The closing of switch *c1* has no immediate effect. The closing of switch *c2* completes circuits Nos. 6 and 8 to energize relays *E* and *F* respectively, closing switches *e1*, *e2*, *f1*, *f2*, *f3* and *f4* 15 and opening switch *f5*. The closing of switches *e1* and *e2* has no immediate effect. The opening of switch *f5* breaks circuits Nos. 17 and 19 to the main street go and cross street stop signals but the closing of switch *f2* immediately establishes 20 circuits Nos. 16 and 18 to maintain these signals in their former condition. The operation of the switches *f1*, *f3* and *f4* connect the remainder of the lamps to the secondary timer so that it may thereafter control the signals but no 25 circuits are immediately completed thereby. Thus a traffic actuation occurring during the Main idle period has resulted in an operation of the relay *F* immediately placing the signals under control of the secondary timer without 30 effecting an immediate change of signals.

Since the condition of the circuits is the same in the Main run period as in the Main idle period, except that motor coil *H2* is operating, a first traffic actuation occurring during the Main run 35 period has the same effect in immediately transferring control of the signals from switch *f5* to the secondary timer without immediate change of signals. Thus, during both the Main idle and Main run periods right of way always remains 40 with the main street irrespective of traffic actuations.

At the end of the Main run period switch *h1* is closed to complete circuit No. 15 to display the amber caution signal to the main street during the change period, the main street green and cross street red signals continuing. If desired, a slightly different wiring may be used by means of which the main street green signal may be extinguished during this period as is common practice in certain cities. At the same time, switch *h1* is opened and switch *h9* is closed to transfer control of relays *E* and *F* from circuits Nos. 6 and 8 to circuits Nos. 7 and 9. If necessary, switch *h9* may be closed slightly before switch *h1* is opened to insure continuity 50 of the relay positions. Thereafter, relays *E* and *F* may remain energized when relay *C* is later released.

At the end of the change period, switches *h6* and *h1* are opened to extinguish the main street go, cross street red and main street amber signals and switch *h5* is closed to complete circuits Nos. 10 and 11 for the main street red and cross street green signals respectively, thus transferring right of way to the cross street. These signals are displayed throughout the Cross idle and Cross run periods and the second Change period.

Near the end of the Cross run period, switch *h2* is momentarily closed to complete circuit No. 4 to start motor *B*. While circuit No. 4 is still established the operation of motor *B* closes switch *b* by moving plate *28* into contact with finger *31*, thus completing circuit No. 5 to con- 75

tinue the operation of motor B after circuit No. 4 is broken. Motor B thus continues to operate until plate 28 has moved a quarter turn to bring the next of the notches 29 into engagement with finger 31, opening switch b and breaking circuit No. 5. In this movement, one of the strikers 27 opens switch a, breaking circuit No. 3 and releasing the relay C. The detector relay is thus restored to the proper condition to register another traffic demand from the detector D. The timing of switch h2 is variable and is so adjusted that any vehicle passing the detector too late to enter the intersection during the Cross run period will find the detector relay in condition

15 to register the demand. The release of relay C has no effect since relays E and F are held by circuits Nos. 7 and 9. Entering the second Change period switch h4 is closed to complete circuit No. 12 to show the amber signal in the 20 cross street.

At the end of the second Change period, switch h9 is opened to break circuits Nos. 7 and 9 and release relays E and F. The resultant opening of switches f3 and f4 breaks circuits Nos. 10, 25 11 and 12 to extinguish the main street red, cross street green and cross street amber signals, while the closing of switch f5 completes circuits Nos. 17 and 19 to display the main street green and cross street red signals. Thus, by operation of 30 switch h9 control of the signals has been taken from the secondary timer and restored to switch f5. At the same time, switches h4 and h5 are opened and switch h6 is closed so that the main street green and cross street red signals will be 35 continued if control of the signals is returned to the timer by another traffic demand.

The circuits have now been restored to the condition from which the assumed sequence of operations began.

40 **CASE II.—Operation in response to traffic actuation occurring during cross idle, cross run or change periods**

Referring now to the operation at the second 45 intersection as indicated in Fig. 6, it is assumed that operation begins in the first Change period and that no traffic actuations have occurred for some time previous. Relay F has not been energized by a traffic demand and the signals therefore are not under control of the secondary timer. Circuits Nos. 17 and 19 are complete to display the main street green and cross street red signals.

With the circuits in this condition, an actuation 55 of a detector is assumed to occur, resulting in actuation of coil A, closing of switch a and energizing of relay C as previously described and as indicated in Fig. 6. In Fig. 6 the detector actuation is shown in the Cross Idle period 60 but the same results are obtained in the Cross run or Change periods. The operation of relay C produces no immediate result since switch h1 is open during all of these periods and circuits Nos. 6 and 8 to relays E and F cannot be completed.

Near the end of the Cross Run period switch h2 is momentarily closed as before but cannot complete circuit No. 4 to motor B since relay E has not yet been energized and switch e2 is open. Motor B, therefore, can not operate to open switch a and consequently relay C remains energized.

At the end of the second Change period, switch h1 is closed, completing circuits Nos. 6 and 8 and energizing relays E and F. Relay F operates as

before to transfer control of the signals to the secondary timer. The timer retains control through the succeeding Main idle, Main run, Change, Cross idle, Cross run and second Change periods, changing the signals as previously described and relinquishing control when switch h9 is opened at the start of the second succeeding Main idle period. Switch h2 operates near the end of the Cross run period to reopen switch a and recondition the detector relay for another 10 traffic demand.

15 **CASE III.—Operation in the absence of traffic actuations**

Referring again to the operation at the first 15 intersection as indicated in Fig. 6, the circuits are in the same condition in the second Main idle period as in the first. However, it is assumed that no traffic actuations occur prior to the end of the Main run period. In that case, relay F remains 20 deenergized throughout the succeeding periods, retaining control of the signals through switch f5 to show main street green and cross road red signals. The switches of the timer are operated through their usual cycles but have no effect on 25 the signals since switches f1, f2, f3 and f4 are all open. This state of affairs continues as long as no traffic demands are received from the cross street.

30 **Signal operation—first class intersections**

The wiring at the first class intersections as 35 shown in Fig. 5a is the same as for the second class intersections except that the detectors, detector relays, and relays C, E and F are omitted and the signal lamp circuits are connected directly to the switches of the secondary timer instead of passing through the switches of relay F. The secondary timers therefore control the signals at all times and operate them through the 40 same cycle of changes and by the same sequence of switching operations as the secondary timers at the second class intersections do when they are in control of the signals.

45 **Recapitulation—coordinated system**

Briefly summarized, the master timer and secondary timers provide means for establishing at the first class intersections alternate periods of main street and cross street right of way and at the second class intersections potential periods of cross street right of way alternated with main street right of way periods. At the first class intersections, the usual cautionary change periods may be provided and at the second class intersections potential cautionary periods may be provided. The periods at intersections are coordinated in any desired time relation with those at the other intersections.

At the second class intersections, the secondary 55 timers do not control the signals in the absence of traffic on the cross street, said signals in that case maintaining main street right of way and denying right of way to the cross street. A traffic demand from the cross street occurring during 60 the main street right of way period results in an immediate transfer of signal control to the timer without an immediate change of signals. The timer exercises control until the start of the next main street right of way period and in so doing 65 converts the intervening potential cross road right of way period and cautionary periods into actual cross road right of way and cautionary periods. A traffic demand received during a potential cross road right of way period or one of 70

75

the potential cautionary periods results in a transfer of control to the timer but said transfer is delayed until the start of the succeeding main street right of way period. Control is relinquished 5 by the timer at the start of the second succeeding main street right of way period, the intervening potential periods being converted into actual periods.

10 *Isolated intersections*

For use at an isolated intersection not a part of a coordinated system, the same apparatus is supplied as at the second class intersections except that the master timer is not used. Switches 15 *h10* and *h11* are connected direct to the local distributary *38* and the coils *H1* and *H2* are connected to the local distributary *39*. Thus the idle periods of the timer are eliminated and the go periods are timed entirely by the speed resulting 20 from coils *H1* and *H2*. The timer assumes control of the signals in response to traffic demands from the cross street, the signals otherwise maintaining main street right of way exactly as previously described for the second class 25 intersections.

The foregoing specification describes a preferred form of the invention the details of which may be varied by those skilled in the art without departing from the scope thereof as defined by 30 the appended claims.

The invention claimed is:

1. In a traffic control system for the intersection of a main street and a cross street, traffic signals, time controlled apparatus operating to 35 time a continuous succession of cycles of potential cross street right of way periods alternated with intermediate periods, relay means normally disconnecting said signals from said apparatus and operating said signals directly to indicate main 40 street right of way in the absence of traffic on the cross street, and traffic controlled means connected with said time controlled apparatus and with said relay means to operate the latter to connect said signals to said apparatus in response to the 45 presence of a vehicle approaching the intersection in said cross street to convert the next succeeding potential cross street right of way period into an actual period of right of way for the cross street.

2. A traffic control signal system for the intersection of a main street and a cross street including 50 right of way signals, a traffic actuated detector adapted to be actuated by vehicles approaching the intersection in said cross street, time controlled means operating cyclically for predetermining a continuous succession of spaced potential right of way periods for said cross street, relay means normally maintaining said signals disconnected from said cyclic means and including circuit means operated by said relay means for normally maintaining said signals to indicate 55 right of way to the main street in the absence of actuation of said detector, and means responsive to an actuation of said detector for operating said relay means to disconnect said circuit means and to connect said time controlled means to said signals to indicate right of way to the cross street during a succeeding potential right of way period and means operated by said time controlled means to restore said relay means and 60 circuit means to normal at the end of the cycle including said cross street right of way indication.

3. A traffic control signal system for the intersection of a main street and a cross street including 65 right of way signals, a traffic actuated detector adapted to be actuated by vehicles ap-

proaching the intersection in said cross street, time controlled means timing a continuous succession of cycles of potential right of way periods for said cross street alternated with intermediate periods, switch means and associated conductors for connecting and disconnecting said time controlled means to control said signals, said time controlled means when so connected operating said signals to grant right of way to the cross street during said potential periods and 10 to deny right of way thereto during said intermediate periods, means controlling said signals to deny right of way to the cross street when said time controlled means is disconnected, means operating in response to an actuation of 15 said detector occurring during at least a part of an intermediate period to immediately operate said switch means to connect said time controlled means to operate said signals, and means associated with said time controlled means and 20 operating said switch means for disconnecting said time controlled means after the end of the next succeeding potential cross street right of way period during which right of way is granted to the cross street.

4. A traffic control signal system for the intersection of a main street and a cross street including right of way signals, a traffic actuated detector adapted to be actuated by vehicles approaching the intersection in said cross street, 30 cyclic time controlled means timing a continuous succession of cycles of potential right of way periods for said cross street alternated with intermediate periods, switch means and associated conductors for connecting and disconnecting said time controlled means to control said signals, said time controlled means when so connected operating said signals to grant right of way to the cross street during said potential periods and 35 to deny right of way thereto during said intermediate periods, means controlling said signals to deny right of way to the cross street when said time controlled means is disconnected, means responsive to an actuation of said detector occurring during one of said potential periods and 40 operating said switch means after the end of said one period to connect said time controlled means to operate said signals, and means associated with said time controlled means and operating said switch means for disconnecting said time 45 controlled means after the end of the next succeeding potential cross street right of way period 50 during which right of way is granted to the cross street.

5. A traffic control signal system for the intersection of a main street and a cross street including right of way signals, a traffic actuated detector adapted to be actuated by vehicles approaching the intersection in said cross street, cyclic time controlled means timing a continuous 55 succession of time cycles each consisting of a potential right of way period for the cross street, a potential warning period for the cross street, an intermediate period and a potential warning period for the main street all in sequence, switch means and associated conductors for connecting said time controlled means to control said signals, said time controlled means when so connected controlling said signals to grant right of way to the cross street during said potential cross street right of way periods, to display a cautionary signal to the cross street during said potential cross road warning periods, to grant right of way to the main street during said intermediate periods and to display a cau- 60 65 70 75 76

tionary signal to the main street during said potential main street cautionary periods, means controlling said signals to grant right of way to the main street when said time controlled means is disconnected, means responsive to an actuation of said detector occurring during that part of a cycle including the potential cross road right of way period and both of said potential warning periods and operating said switch means after the beginning of the first succeeding intermediate period to connect said time controlled means to operate said signals, and means associated with said time controlled means and operating said switch means to disconnect said time controlled means after the beginning of the second succeeding intermediate period.

6. In a coordinated traffic control system for the intersections of a main street and a plurality of cross streets, traffic signals at each intersection, time controlled means timing a continuous succession of cycles of spaced potential cross street right of way periods for each of said intersections, said periods at one of said intersections occurring in definite timed relation with those at another of said intersections, traffic actuated detectors at each of said intersections adapted to be actuated by vehicles approaching the intersection in the cross street, relay means normally maintaining the signals at each of said 30 intersections disconnected from said time controlled means and operated directly to indicate right of way to the main street in the absence of actuations of the associated detector, and means responsive to an actuation of the detector at each intersection to operate said relay means to connect said signals thereto to said time controlled means to operate the signals at said intersection to indicate right of way to the cross street during only the next succeeding potential right of way period.

7. In a coordinated traffic control system for the intersections of a main street and a plurality of cross streets, traffic signals at each intersection, time controlled means timing a continuous succession of cycles of spaced potential cross street right of way periods for each of said intersections, said periods at one of said intersections occurring in definite timed relation with those at another of said intersections, a traffic actuated detector at each of said intersections adapted to be actuated by vehicles approaching the intersection in the cross street, switch means and associated conductors for connecting and disconnecting said time controlled means to control the signals at each intersection, said time control means when so connected operating said signals to grant right of way to the cross street during said potential periods and to deny right of way thereto at other times, means controlling said signals to deny right of way to the cross streets when said time controlled means is disconnected, means operating in response to an actuation of a detector occurring during at least a part of an intermediate period for the associated intersection to immediately operate said switch means to connect said time controlled means for operating the signals at said intersection, and means associated with said time controlled means and operating said switch means for disconnecting said time controlled means after the end of the next succeeding potential cross street right of way period.

8. In a coordinated traffic control system for the intersections of a main street and a plurality of cross streets, traffic signals at each intersection, time controlled means timing a continuous

succession of cycles of spaced potential cross street right of way periods for each of said intersections, said periods at one of said intersections occurring in definite timed relation with those at another of said intersections, a traffic actuated detector at each of said intersections adapted to be actuated by vehicles approaching the intersection in the cross street, switch means and associated conductors for connecting and disconnecting said time controlled means to control the signals at each intersection, said time controlled means when so connected operating said signals to grant right of way to the cross street during said potential periods and to deny right of way thereto at other times, means controlling said signals to deny right of way to the cross streets when said time controlled means is disconnected, means responsive to actuation of a detector occurring during one of said potential periods for the associated intersection and operating said switch means after the end of said period to connect said time controlled means to operate the signals at said intersection, and means associated with said time controlled means and operating said switch means for disconnecting said time controlled means after the end of the next succeeding potential cross street right of way period.

9. In a coordinated traffic control system for the intersections of a main street and a plurality of cross streets, traffic signals at each intersection, time controlled means timing for each intersection a continuous succession of timed cycles each consisting of a potential right of way period for the cross street, a potential warning period for the cross street, an intermediate period and a potential warning period for the main street all in sequence, said time cycles for one intersection having a definite time relation with those of another intersection, switch means and associated conductors for connecting said time controlled means to control the signals at each intersection, said time controlled means when so connected controlling said signals to grant right of way to the cross street during said potential cross street right of way periods to display a cautionary signal to the cross street during said potential cross road warning period, to grant right of way to the main street during said intermediate periods and to display a cautionary signal to the main street during said potential main street cautionary periods, means controlling said signals at each intersection to grant right of way to the main street when said time controlled means is disconnected, a traffic actuated detector at each of said intersections adapted to be actuated by vehicles approaching the intersection in the cross street, means responsive to an actuation of a detector occurring during that part of the cycle for the associated intersection including the potential cross road right of way period and both of said potential warning periods and operating said switch means after the beginning of the first succeeding intermediate period to connect said time controlled means to operate the signal at said intersection, and means associated with said time controlled means and operating said switch means to disconnect said time controlled means after the beginning of the second succeeding intermediate period.

10. In a traffic control system for the intersection of a main street and a cross street having right of way traffic signals and circuits for energizing the same, means responsive to traffic in the cross street, an electric motor operating at a predetermined time rate and a shaft and switches

- operated thereby to energize said signal circuits when connected thereto through continuous successive cycles in each of which right of way is accorded for time periods to the main and cross streets alternately; relay means connected with said signal circuits and switches to control connection of the latter and having a normal deenergized condition to disconnect said circuits from said switches and to energize directly the main street right of way signals and said relay means having an energized condition to interrupt direct energization of said main street right of way signals and to connect said circuits to said switches, and an operating circuit for said relay means connected with said traffic responsive means and including a switch closed by said shaft in its main street right of way period to energize said relay means during the latter period responsive to traffic on the cross road, and an auxiliary circuit for said relay means including a switch operated by said shaft to maintain said relay means so energized through the cycle until the beginning of the following main street right of way period.
11. In a traffic control system for the intersection of a main street and a cross street having go, stop and cautionary signals for the main and cross streets respectively and circuits therefor, traffic actuated means in the cross street, an electric motor operating at a predetermined time rate and a shaft and switches operated thereby to energize said signal circuits when connected thereto in continuously repeated time cycles including a right of way period for the main street, a potential cautionary change period for the main street, a potential right of way period for the cross street and a potential cautionary change period for the cross street all in sequence in each cycle, other switches interposed in said signal circuits, electromagnetic means operating said other switches when deenergized to interrupt connection between the signal circuits and the switches of said mechanism and to connect the main street "go" signal and cross street "stop" signal directly to a power supply to energize the same, and said electromagnetic means when energized connecting said circuits only to the switches of said mechanism, and means operating responsive to actuation of said traffic actuated means to energize said electromagnetic means in said main street right of way period, said last named means including a switch closed by actuation of said traffic actuated means, a switch closed by

said shaft in the main street right of way period and a circuit through said switches for energizing said electromagnetic means when closed, and a stick circuit for said electromagnetic means including a switch closed by said shaft to maintain said electromagnetic means so energized only through the main street caution period and the cross street right of way and caution periods. 5

12. A traffic control signal system for the intersection of a main street and a cross street including right of way signals, a traffic actuated detector adapted to be actuated by vehicles approaching the intersection in said cross street, time controlled means timing a continuous succession of cycles of potential right of way periods 10 for said cross street alternated with intermediate periods, switch means and associated conductors for connecting and disconnecting said time controlled means to control said signals, said time controlled means when so connected operating 15 said signals to grant right of way to the cross street during said potential periods and to deny right of way during said intermediate periods, circuit means for operating said signals to grant right of way to the main street and deny right 20 of way to the cross street when energized, relay means having a normal unoperated condition for energizing said circuit means and for controlling said switch means in such normal condition to maintain said signals disconnected from said time 25 controlled means, and having an operated condition for deenergizing said circuit means and connecting said signals to said time controlled means, an operating circuit for said relay means including a switch device closed by actuation of said 30 detector and a switch closed by said time controlled means only during said intermediate period, a holding circuit for said relay means including a switch closed by said time controlled means only in said cross street potential right of 35 way period, and a holding device for maintaining said switch device operated after actuation until right of way is granted to the cross street in response to such actuation, releasing means for said holding device and an operating circuit for 40 said releasing means including a switch closed by said time controlled means only near the end of said cross street potential right of way period and a switch closed by said relay means in the 45 energized condition of the latter. 50
